UNITED STATES PATENT OFFICE.

JAMES T. ANTHONY, OF SOUTH ORANGE, NEW JERSEY, ASSIGNOR TO GENERAL REFRactories COMPANY, OF PHILADELPHIA, PENNSYLVANIA, A CORPORATION OF PENNSYLVANIA.

ARCH BRICK.

Application filed November 3, 1927. Serial No. 230,811.

My invention relates to refractory arches for locomotives and particularly to a novel brick adapted for use at a particular point in the arch.

5 In locomotives of a certain type, the circulating tubes or so-called arch tubes, are by reason of the design, located at their support ends at a point comparatively close to the grate; in other words, the throat 10 sheet is shallow with the result that the firing clearance between the bottom of the arch and the top of the grates is inadequate. Consequently the coal as it is thrown through the fire box door, strikes the arch, 15 is deflected downward and forms a bank across the fire box at the throat sheet, leaving an intervening space between the throat sheet and the bank of coal which is not covered by fuel, and through which cold 20 air enters; or if the coal is not banked up at the forward end of the grate, the space at that point, the space next to the throat sheet, becomes filled solid with coal which eventually burns out leaving a mass of 25 cinders and ashes at that point, the removal of which is difficult.

The brick illustrated herein is designed to obviate this difficulty. It is of the common form so far as the horizontally extending portion of the brick is concerned, but I have provided diagonally downwardly and forwardly extending marginal flanges suitably hollowed out or socketed to fit the tubes. When installed on the inclined arch tubes, the brick occupies a substantially horizontal plane, thus leaving a substantial clearance between the grate and the arch and avoiding the difficulties heretofore encountered.

35 The invention will be more readily understood by reference to the accompanying drawings, in which;

Fig. 1 is a longitudinal section through a locomotive fire box having an arch to 45 which my improved bricks have been applied;

Fig. 2 is a side elevation of one of the middle bricks employed in the arch,

Fig. 3 is an end view thereof, and

50 Fig. 4 is a sectional view taken on substantially the line 4-4 of Fig. 1.

As shown in the drawings, the brick comprises a body portion 10 of generally arcuate form, the center portion of the brick 55 being thicker than at its sides. At each

side the brick has a downwardly extending flange, 11 of increasing depth toward the forward edge of the brick. A tube engaging socket, 12 is provided along the side of the flange for engagement with the co-operating circulating tubes. Interiorly of the flange, I provide a body of material, 13 that acts to stiffen and support the flange.

60 Bricks constructed in this manner may be molded without difficulty and due to 65 the design of the projecting parts, is not likely to be easily broken in handling.

70 Preferably the angle of inclination of the depending flanges and their tube supporting sockets will be such that the brick will 75 remain substantially horizontal, although the tubes are quite acutely inclined.

It is obvious that modifications may be 75 made in the design here illustrated, and I do not wish to be limited except as indicated in the appended claims.

I claim:

1. In a locomotive fire box, the combination with the grate and throat sheet, of circulation tubes extending upward from the 80 throat sheet and a row of bricks extending between the circulation tubes and positioned adjacent to the throat sheet, the tubes being inclined downwardly and forwardly at their point of engagement with the throat sheet, 85 the bricks having depending side flanges of increasing depth forwardly and provided with tube engaging sockets extending parallel to the bottom edge of the flanges.

2. In a locomotive fire box, the combination of a throat sheet and circulation tubes, a row of bricks extending across the fire box adjacent to the throat sheet, the side margins of the bricks in said row being extended downwardly and of increasing 95 depth forwardly, the lower margins of the flanges being provided with tube-engaging sockets.

3. The combination with downwardly and forwardly inclined arch tubes of arch bricks 100 for cooperation with said tubes, the sides of said bricks being extended downward and of increasing depth from back to front thereof whereby said bricks may be laid on said inclined tubes and remain in a substantially horizontal position, notwithstanding 105 the incline of the tubes.

I testify whereof I have affixed my signature.

JAMES T. ANTHONY.
